UNITED STATES PATENT OFFICE.

FORREST L. CANTRALL, OF OAKLAND, CALIFORNIA, ASSIGNOR TO HARRY M. BENNETT, OF OAKLAND, CALIFORNIA.

AUTOMOBILE-ENGINE STOP.

1,377,002.

Specification of Letters Patent. Patented May 3, 1921.

Application filed April 14, 1919. Serial No. 289,855.

To all whom it may concern:

Be it known that I, FORREST L. CANTRALL, a citizen of the United States, and a resident of Oakland, county of Alameda, and State 5 of California, have invented a new and useful Automobile-Engine Stop, of which the following is a specification.

My invention relates to means for automatically stopping the operation of an automobile engine.

An object of the invention is to provide means, operating automatically, for interrupting the spark of an automobile engine so that when the driver is away from the car, 15 the engine can not be left running.

Another object of the invention is to provide a device of the character described embodying automatically operating means for admitting additional air into the intake 20 manifold while the engine is running.

The invention possesses other objects and features of advantage, some of which, with the foregoing, will be set forth in the following description of the preferred form of my 25 invention which is illustrated in the drawings accompanying and forming part of the specification. It is to be understood that I do not limit myself to the showing made by the said drawings and description, as I may 30 adopt variations of the preferred form within the scope of my invention as set forth in the claims.

Referring to the drawings:

Figure 1 is a side elevation of a portion of an automobile engine with the device of my 35 invention applied thereto. A portion of the gear shift lever by which my device is operated is also shown on the left side of the figure.

Fig. 2 is a vertical sectional view taken in the plane 2—2 of Fig. 1.

Fig. 3 is a horizontal sectional view taken in the plane 3—3 of Fig. 2.

Fig. 4 is a horizontal sectional view 45 through a portion of my device, taken in the plane 4—4 of Fig. 2. A diagram of the spark circuit is also shown.

Fig. 5 is a vertical sectional view through 50 a portion of my device, taken in the plane 5—5 of Fig. 4.

Owners of automobile delivery trucks have found that a large saving in fuel could be effected if the drivers could be induced to shut off the engine when the vehicle is left 55 standing during deliveries. This has been found to be impracticable and it is therefore

one of the objects of my invention to provide a means of automatic control, the operation of which is initiated when the transmission system of the car is rendered inoperative, as 60 it necessarily must be when the car is brought to rest without stopping the engine. In the transmission system I include change gears, clutch and other mechanism between the engine and the driving axle.

In general terms the structure of my device comprises a base upon which three cylinders containing pistons are arranged. The base is connected to the intake manifold between the butterfly valve and the cylinders, 70 and is provided with a valve operated by movement of the gear shift lever. Movement of the valve operates to place either one of the cylinders in communication with the intake manifold so that the partial 75 vacuum therein is utilized to move the piston in the connected cylinder. One of these pistons constitutes a valve for the admission of additional air into the manifold under certain conditions. The other piston operates a circuit closing and opening mechanism for controlling the spark circuit, and movement of this piston is regulated by its connection to the piston in the third cylinder which constitutes a dash pot.

If the engine of the car is left running, the gear shift lever must be brought to neutral position. Such movement of the lever effects a connection of the manifold to the cylinder containing the piston which operates the circuit closing and opening mechanism, and within a predetermined interval, the spark is discontinued and the engine stops, upon which the piston and circuit closing and opening mechanism return to first 95 position which restores the spark circuit.

When the engine is again started and the gear shift lever moved, the other cylinder is connected to the manifold and the valve therein permits air to be drawn into the 100 manifold under heavy load or high speed conditions.

In detailed terms my invention comprises a base 2 provided with a nipple 3 adapted to be connected into the intake manifold 4 of an engine 6 by the elbow 7. The base is formed with the passage 8 through the nipple and opening into a cylindrical bore 9 in which a slide valve 10 is adapted to be reciprocated. An apertured cap 11 closes the 110 end of the bore. A spring 12 moves the valve in one direction and a cam 13 moves

it in the opposite direction. The cam is formed on the slide 14 arranged in the guide sleeve 16 and connected by the rod 17 to the gear shift lever 18 of the car. The slide 5 valve 10 is provided with two annular chambers separated by the flange 19, and movement of the gear shift lever, in connection with the spring 12, effects a movement of the valve 10 so that the flange 19 is either to 10 one side or the other of the opening of the passage 8 into the bore 9. Opening into the bore 9, one on each side of the flange 19, are passages 21 and 22, and movement of the flange 19 to one side or the other of the 15 opening of the passage 8 thus places that passage in communication with either passage 21 or 22 as the case may be.

Arranged on the base 2 is a cylinder 23, into the bottom of which the passage 21 20 opens. A piston 24 is disposed in the cylinder, and a spring 26 tends to retain the piston at the top of the cylinder. Adjacent the cylinder 23 a cylinder 27 is also disposed on the base 2, and provided with a piston 28 25 through which a by-pass 29 is formed. The size of the by-pass is controlled by the sleeve 31 inclosing and threaded to the piston rod 32, the lower end of the sleeve lying adjacent the upper opening of the by-pass. The 30 cylinder 27 is filled with oil, and by turning the sleeve, the by-pass may be opened or closed the desired amount to regulate the speed at which the piston 28 moves. A lock nut 32 fixes the sleeve on the piston rod in 35 the desired adjustment. Fixed in the piston 24 is a rod 33 passing loosely through the cap 34 and provided with a rigidly fixed arm 35 which is formed with a yoke 36 adapted to seat in an annular groove in the head of 40 the sleeve 31 so that adjustment of the sleeve is not interfered with. The two pistons 24 and 28 are thus connected together and the speed with which the piston 24 moves is controlled by the piston 28. Intermediate 45 the ends of the cylinder 23 a block 37 formed in two parts is disposed, the outer portion 37^a being separated from the main portion by a layer 38 of insulating material. A chamber 39 opening into the cylinder 23, 50 as best shown in Fig. 4, is formed in the block and contains the circuit closing and opening means actuated by the piston 24. Arranged in the block 37^a are two pins 41 and 42 which project into the chamber 39. 55 The inner end of pin 42 provides a contact point, and on pin 41 is pivotally mounted the switch lever 43 pressed by the spring 44 into contact with the pin 42 when permitted to move in that direction. The under side 60 of the switch lever is provided with a raised seat 47 in which the pin 48 of insulating material is adapted to lie, holding the lever out of contact with the pin 42. The pin 48 is fixed on the lever 49 pivoted in the block 65 37 by pin 50, and extending adjacent the

piston 24, where its end lies within a recess 51 cut in the piston.

The outer ends of the pins 41 and 42 form terminals to which are connected conductors 53, Fig. 4. One of these conductors is connected into that portion 54 of the spark circuit running from the magneto 55 to the distributor 56, and the other conductor is grounded on the engine 6. A spark plug 57 for one cylinder only is shown in Fig. 4. 70 One side of both magneto and spark are shown grounded on the engine according to usual practice. The device is thus connected in parallel with the spark, and closing the circuit through the switch lever 43 75 short circuits the magneto and interrupts the spark.

Arranged on the base 2 adjacent the cylinder 23 is the cylinder 61, having the slot 62 formed in the wall thereof. The passage 85 22 opens into the bottom of the cylinder and a piston valve 63 is disposed in the cylinder and normally held in the upper part thereof by the spring 64. An annular chamber 66 is formed about the piston valve and lies opposite the slot 62 when the piston is in its 90 upper position. Passages 67 in the piston connect the chamber 66 with the inside of the cylinder. The piston valve 63 is sufficiently loose in the cylinder to permit air to 95 pass to and from the chamber above the piston during its movement. The gradual passing of the air to or from the chamber prevents too abrupt movement of the piston.

Operation.—The engine of the car is assumed to be running. The piston 24 and switch mechanism are in the positions shown in Figs. 2 and 5, the circuit through the conductors 53 being interrupted. With the gear lever out of neutral, the cam 13 is in either 100 position 68 or 69, and the valve 10 is thrown to the left (of Fig. 3) by the spring 12 so that passage 8 is connected to passage 22, that is, the manifold is connected to the cylinder 61. At low engine speeds, with small 110 loads the butterfly valve will be partially closed and the vacuum in the manifold relatively high. The piston valve 63 is, therefore, sucked downwardly, shutting off the intake of air through the slot 62 as the upper 115 end of the piston covers the slot. At low engine speeds with heavy loads, or at high speeds, the butterfly valve will be open and the vacuum in the manifold relatively low. The piston valve therefore rises under the influence of the spring 64 so that additional air is drawn into the fuel mixture, through the slot 62. During operation, therefore, the piston valve responds to the degree of 120 vacuum in the manifold, admitting or shutting off the additional air according to the demand of the engine.

When the car is stopped, the gear shift lever must be brought to neutral position. This moves the cam 13 across the end of valve 130

10, as shown in Fig. 3, moving the valve to the right (of Fig. 3) and connecting the passage 8 to passage 21, that is, the manifold is connected to the cylinder 23. If the engine is left running, the partial vacuum in the manifold sucks the piston 24 downwardly at a speed determined by the dash pot adjustment. After a short movement of the piston the upper shoulder of the recess 5 51 engages the end of the lever 49, which then moves with the piston, about its pivot 50, unseating the pin 48, Fig. 5, from the seat 47 and allowing the spring pressed switch arm 43 to drop into contact with terminal pin 42. This completes a short circuit of the magneto, interrupting the spark and stopping the engine. With the stopping of the engine, the vacuum is released and, under the influence of the spring, the piston rises, 10 lifting the switch lever and breaking the short circuit. The dash pot mechanism is adjusted to permit the piston 24 to complete a stroke in from twenty to thirty seconds, so that in starting there is ample time for the driver to crank his car, get in and shift his gears, before the device again interrupts the spark. It will be perfectly obvious from the above that instead of the switch lever completing a short circuit in a grounded system 15 it may be connected in series with the magneto circuit, and act as a make-and-break device therein. In this case the switch lever is normally in contact with the terminal pin 42 and downward movement of the piston 25 breaks this contact to interrupt the spark.

I claim:

1. An attachment for automobile engines comprising means for stopping the engine, means operated by the engine for actuating said stopping means, and means effective when the transmission system of the automobile is inoperative for initiating the operation of said actuating means.
2. An attachment for automobile engines comprising means for interrupting the spark, means operated by the engine for actuating said interrupting means, and means effective when the transmission system of the automobile is inoperative for initiating the operation of said actuating means.
3. An attachment for automobile engines comprising means for short circuiting the ignition circuit, means operated by the engine for actuating said short circuiting means, and means effective when the transmission system of the automobile is inoperative for initiating the operation of said actuating means.
4. An attachment for automobile engines comprising means for stopping the engine, a cylinder, a piston in said cylinder for actuating said stopping means, and means for connecting said cylinder to the intake manifold of the engine whereby said cylinder is 55 vacuumized.
5. An attachment for automobile engines comprising means for stopping the engine, a cylinder, a piston in said cylinder for actuating said stopping means, and means operated when the transmission gears are shifted to neutral position for connecting said cylinder to the intake manifold of said engine whereby said cylinder is vacuumized. 70
6. An attachment for automobile engines comprising means for stopping the engine, a cylinder, a piston in said cylinder for actuating said stopping means, a passage connecting said cylinder to the intake manifold of the engine, a slide valve for opening and closing said passage, and means operated when the transmission system of the automobile is rendered inoperative for moving said slide valve to open said passage. 75
7. An attachment for automobile engines comprising means for stopping the engine, a cylinder, a piston in said cylinder for actuating said stopping means, a passage connecting said cylinder to the intake manifold of the engine, a slide valve for opening and closing said passage, and a cam mediate 80 connected to the gear change lever of the automobile for moving said slide valve to open said passage. 85
8. An attachment for automobile engines comprising means for stopping the engine, a cylinder, a piston in said cylinder for actuating said stopping means, a passage connecting said cylinder to the intake manifold of the engine, a slide valve for opening and closing said passage, a cam mediate 90 connected to the gear change lever of the automobile for moving said slide valve in one direction, and resilient means for moving said slide valve in the other direction. 95
9. An attachment for automobile engines comprising a cylinder, a piston in said cylinder, circuit closing and opening means associated with the ignition circuit and operated by said piston, and means for connecting said cylinder to the intake manifold of said engine. 105
10. An attachment for automobile engines comprising a cylinder, a piston in said cylinder, circuit closing and opening means associated with the ignition circuit and operated by said piston, and means associated with the gear shift lever of the automobile for connecting said cylinder to the intake manifold of said engine. 110
11. An attachment for automobile engines comprising a cylinder, a piston in said cylinder, circuit closing and opening means associated with the ignition circuit and operated by said piston, means for connecting said cylinder to the intake manifold of said engine, and a spring interposed between said cylinder and said piston. 115
12. An attachment for automobile engines comprising a cylinder, a piston in said cylinder, circuit closing and opening means associated with the ignition circuit and operated by said piston, means for connecting said cylinder to the intake manifold of said engine, and a spring interposed between said cylinder and said piston. 120
13. An attachment for automobile engines comprising a cylinder, a piston in said cylinder, circuit closing and opening means associated with the ignition circuit and operated by said piston, means for connecting said cylinder to the intake manifold of said engine, and a spring interposed between said cylinder and said piston. 125
14. An attachment for automobile engines comprising a cylinder, a piston in said cylinder, circuit closing and opening means associated with the ignition circuit and operated by said piston, means for connecting said cylinder to the intake manifold of said engine, and a spring interposed between said cylinder and said piston. 130

- ciated with the ignition circuit and operated by said piston, means for connecting said cylinder to the intake manifold of said engine, and means for regulating the speed of 5 movement of said piston.
13. An attachment for automobile engines comprising a cylinder, a piston in said cylinder, circuit closing and opening means associated with the ignition circuit and operated 10 by said piston, means associated with the gear shift lever for connecting said cylinder to the intake manifold of said engine, a second cylinder adapted to contain oil, and a piston connected to the first mentioned 15 piston arranged in said second cylinder for controlling the speed of movement of the first piston.
14. An attachment for automobile engines comprising a cylinder, a piston in said 20 cylinder, circuit closing and opening means associated with the ignition circuit and operated by said piston, means associated with the gear shift lever for connecting said cylinder to the intake manifold of said engine 25 whereby said piston is moved to operate said circuit closing and opening means, and a spring for moving said piston in the opposite direction to operate said circuit closing and opening means.
15. An attachment for automobile engines comprising a cylinder, a piston having 30 a recess and arranged in said cylinder, a pivoted lever extending into said recess whereby movement of the piston effects a 35 movement of the lever toward the end of its stroke, circuit closing and opening means operated by said lever, and means associated with the gear shift lever for connecting said cylinder to the intake manifold of 40 said engine.
16. An attachment for automobile engines comprising a cylinder, a piston having a recess and arranged in said cylinder, a pivoted lever extending into said recess 45 whereby movement of the piston effects a movement of the lever toward the end of its stroke, circuit closing and opening means operated by said lever, means associated with the gear shift lever for connecting said 50 cylinder to the intake manifold of said engine whereby the piston is moved to operate said lever, and a spring interposed between the piston and the cylinder for effecting a recovery movement of said piston to operate 55 said lever.
17. An attachment for automobile engines comprising a cylinder, a piston having a recess and arranged in said cylinder, a pivoted lever extending into said recess 60 whereby movement of the piston effects a movement of the lever toward the end of its stroke, circuit closing and opening means operated by said lever, means associated with the gear shift lever for connecting said 65 cylinder to the intake manifold of said engine whereby the piston is moved to operate said lever, a spring interposed between the piston and the cylinder for effecting a recovery movement of said piston to operate said lever, and means for regulating the speed of movement of said piston.
18. An attachment for automobile engines comprising a base having a passage therethrough and adapted to be connected into the intake manifold of said engine, a pair of cylinders on said base, a slide valve in said base for connecting the passage therethrough with either of said cylinders, means associated with the gear shift lever of said automobile for operating said slide valve, circuit closing and opening means associated with the ignition circuit of the engine, a piston in one of said cylinders for operating said circuit closing and opening means, means for regulating the speed of movement of said piston, a piston valve in the other of said cylinders for controlling the admission of air thereinto, and means for effecting the recovery movement of both the piston and the piston valve.
19. An attachment for automobile engines, comprising means for stopping the engine, a cylinder, a piston in said cylinder for actuating the stopping means, a second cylinder, a piston valve in said second cylinder for controlling the admission of air thereinto, and means associated with the gear shift lever for connecting either of said cylinders with the intake manifold of said engine.
20. An attachment for automobile engines, comprising means for stopping the engine, a cylinder, a piston in said cylinder for actuating the stopping means, a second cylinder, a piston valve in said second cylinder for controlling the admission of air thereinto, means associated with the gear shift lever for connecting either of said cylinders with the intake manifold of said engine, and means for effecting the recovery movement of said piston and piston valve.
21. An attachment for automobile engines, comprising means for stopping the engine, a cylinder, a piston in said cylinder for actuating the stopping means, a second cylinder, a piston valve in said second cylinder for controlling the admission of air thereinto, means associated with the gear shift lever for connecting either of said cylinders with the intake manifold of said engine, means for effecting the recovery movement of said piston and piston valve, and means for regulating the speed of movement of said piston.
- In testimony whereof I have hereunto set my hand at San Francisco, California, this 8th day of April, 1919.
